FLUE-LINER DRAIN

Edward Berndt, Chicago, Ill.

Application March 17, 1945, Serial No. 583,286

1 Claim. (Cl. 72—94)

This invention relates to the construction of flue- or chimney-liners of the type which have been found essential to protect the masonry against excessive condensation which takes place in the flue or chimney, particularly when used for gas-fired boilers or furnaces. In situations where such excessive condensation takes place in the flue or chimney the masonry deteriorates, sometimes quite rapidly, often causing damage to the interior of the house. The mortar between the bricks, being especially vulnerable to such flue or chimney condensation tends to disintegrate. Allowed to continue unchecked a hazardous condition of the flue or chimney above the roof may result. Below the roof, the disintegrating mortar permits a seepage through into the interior plastered walls and ceilings.

Heretofore it has been a practice to protect flues or chimneys by installing a liner. At the lower end the liner has to be provided with a pipe to drain off the condensation into the house sewer. However, such constructions have afforded no protection against the clogging of the drain by the accumulation of soot, leaves, and twigs in the bottom of the flue-liner, neither have they allowed for easy repair or replacement of the drain, nor have they permitted a ready inspection of the drain or the flue-liner itself, to determine conditions thereof.

The main objects of this invention, therefore, are to provide an improved form of flue- or chimney-liner construction which locates the drainage connection entirely outside the flue or chimney where it is accessible for convenient attachment of the drain pipe and a subsequent inspection and repair as occasion may require; to provide an improved construction of a flue-liner drain of this kind adapted for attachment to the end of a flue-liner section extending to the exterior of the flue; to provide a flue-liner drain with a removable part which will permit inspection of the drain outlet and the flue-liner and allow for a removal of accumulations in the flue-liner; and to provide a device of this kind which is simple and economical to manufacture, easy of attachment, and permanently effective in its functioning.

In the accompanying drawing—

Figure 1 is a cross-sectional view of a flue equipped with a flue-liner, at the lower end of which is attached a flue-liner drain constituting a preferred embodiment of this invention;

Figure 2 is an enlarged, partly end and partly cross-sectional view of a flue-liner drain of the preferred embodiment;

Figure 3 is a fragmentary detail taken in the line 3—3 of Figure 2.

The drawings show a flue or chimney 4, of conventional construction, wherein has been arranged a flue-liner 5. Near the lower end of the liner is a branch 6, for connection with the smoke outlet of the main heating plant, and a second branch 7 for connection of an auxiliary hot water heater.

10 A flue-liner drain 8 embodying this invention and formed with a sump or drain pocket 9 and equipped with an inspection door 10 is secured to the outer end of the horizontal flue-liner section 11.

15 In the form herein shown the flue-liner drain is a cast aluminum sleeve. Although such a casting is preferred, the flue-liner drain could be formed of sheet metal if desired. The axis of the sleeve is set at a slight angle so that when 20 telescopically connected with the section 11 it conforms to the slant thereof and the drain pocket 9 is approximately vertical.

25 As is evident from the drawing, the pocket 9 is in the nature of an extension formed near the outer end of the sleeve 8. The flat bottom 12 is offset radially from the circumference of the sleeve and with the closely-spaced parallel vertical side walls 13 and the more distantly-spaced vertical end walls 14, constitutes a narrow, elongated pocket of U-shaped cross section both in the direction of the axis of the sleeve 8 and transversely thereto.

30 A threaded ring 15 is embedded or otherwise secured in the bottom 12 so that a drain pipe 35 16 may be attached thereto and suitably connected with the house sewer.

35 In order to protect the drain 16 from being clogged by accumulations of soot, leaves, and twigs falling down through the flue-liner 5, an 40 inverted U-shaped screen 17 is fitted into the pocket 9. A grip 18 is suitably secured thereto by means of nuts 19 so that the screen may be easily removed and replaced.

45 The inspection door 10 has a lug 20 formed on the lower end which fits over the upper end of the outer side wall 13 of the pocket 9 and in a way serves to hinge the door on the sleeve 8. At its upper end, the door is provided with an apertured lug 21 registering with a similarly-apertured lug 22 on the adjacent part of the sleeve 8. A bolt 23 extends through the registering apertures in the lugs 21 and 22 and accommodates a wing nut 24 by which the door 10 is secured in place.

50 55 An arrangement of a flue-drain in accordance

with this invention permits the condensation formed in the flue-liner 5 to be readily drained into the house sewer, thereby precluding the possibility of any accumulations of moisture in or at the bottom of the flue-liner. If any leaves or twigs or other foreign matter finds its way into the flue-liner, they will gravitate toward the pocket 9 of the flue drain where they will be caught by the screen 17 so as to preclude the possibility of clogging the drain pipe 16.

As occasion may require, the door 10 may be very easily removed, not only to permit an inspection of the condition around the drain pocket 9, but if necessary remove any accumulation of material around the screen 17. To facilitate this the screen 17 may be taken out, cleaned, and replaced. Such removal of the door 10 permits a mirror to be inserted for the purpose of examining the condition of the vertical flue-liner 5.

Variations and modifications in the details of structure and arrangement of the parts may be resorted to within the spirit and coverage of the appended claim.

I claim:

A combination flue-liner drain and inspection unit comprising an angular tubular member having one end thereof adapted for telescopic attachment to a flue liner and the other end projecting outwardly and downwardly exteriorly of said flue, a closure plate removably secured to said other end of said member to permit inspection of said flue liner when said plate is removed, a condensation sump formed in said member below said plate to receive condensation from said tubular member, and a connection to said sump for the attachment of a drain pipe.

EDWARD BERNDT.
